(57) CLAIM

The ornamental design for a handbag, as shown and described.

DESCRIPTION

FIG. 1 illustrates a perspective open view of the handbag, showing a first embodiment of my new and ornamental design;

FIG. 2 illustrates a front open view thereof;

FIG. 3 illustrates a back open view thereof;

FIG. 4 illustrates a left side open view thereof;

FIG. 5 illustrates a right side open view thereof;

FIG. 6 illustrates a top open view thereof;

FIG. 7 illustrates a bottom open view thereof;

FIG. 8 illustrates a perspective open view of the handbag, showing a second embodiment of my new and ornamental design;

FIG. 9 illustrates a front open view thereof;

FIG. 10 illustrates a back open view thereof;

FIG. 11 illustrates a left side open view thereof;

FIG. 12 illustrates a right side open view thereof;

FIG. 13 illustrates a top open view thereof;

FIG. 14 illustrates a bottom open view thereof;

FIG. 15 illustrates a perspective closed view of the handbag, showing a first embodiment of my new and ornamental design;

FIG. 16 illustrates a front closed view thereof;

FIG. 17 illustrates a back closed view thereof;

FIG. 18 illustrates a left side closed view thereof;

FIG. 19 illustrates a right side closed view thereof;

FIG. 20 illustrates a top open closed thereof;

FIG. 21 illustrates a bottom closed view thereof;

FIG. 22 illustrates a perspective closed view of the handbag, showing a second embodiment of my new and ornamental design;

FIG. 23 illustrates a front closed view thereof;

FIG. 24 illustrates a back closed view thereof;

FIG. 25 illustrates a left side closed view thereof;

FIG. 26 illustrates a right side closed view thereof;

FIG. 27 illustrates a top open closed thereof; and,

FIG. 28 illustrates a bottom closed view thereof.

The portions of the handbag shown in the figures, in broken lines, attached hereto, form no part of the claimed design.
